UNITED STATES PATENT OFFICE

CHARLES MAYER, OF PARIS, FRANCE

PISTON PUMP FOR MEDICAL PURPOSES

Application filed April 22, 1929, Serial No. 357,275, and in France April 30, 1928.

The present invention has reference to a piston pump for medical purposes of the valveless type and as its object embraces the provision of a pump of the above character wherein improved operating means is provided for imparting to the piston a continuous rotary and reciprocatory movement.

Briefly stated the invention may be said to consist in the provision of a crank directly connected with the piston for effecting rotation thereof and provided with a finger movable in a cam slot which is fixed relatively to the pump barrel for simultaneously imparting to the piston reciprocatory movement.

The invention also embraces the provision of a piston pump of the above character wherein the parts are constructed so that they may be rapidly assembled and taken apart with a view of sterilizing the elements.

Other objects as well as the nature, characteristic features and scope of the invention will be more readily apparent from the following description taken in connection with the drawing and pointed out in the claims forming a part of this specification.

The accompanying drawing illustrates, by way of example only, a medical pump constructed in accordance with the invention, and in which:

Figure 1 is a vertical longitudinal section of the pump in its entirety.

Figure 2 is a partial section of the pump barrel, made through a plane at right angles to Figure 1 showing the suction and delivery ports.

Figures 3 and 4 are diagrammatic views showing the cycle of operation of the pump.

Referring more particularly to the accompanying drawing in which similar characters of reference designate corresponding parts throughout the several views there is provided a pump barrel in the form of a glass cylinder or tube 1 perfectly calibrated internally and on the upper part of which fits the bottom 2 of a metal armature extending down to the lower edge of the tube 1 so as to constitute a socket 3 screw-threaded at 4. The armature is provided with arms 5 and with perforated bosses 6 and 7 which constitute nozzles on which are secured the suction and

delivery pipes (not shown in the drawing). The passage-ways of the nozzles coincide with orifices or ports 8 and 9 provided through the wall of the tube 1. The armature is sealed on the glass by any suitable cement resistant to a prolonged stay in boiling water or in sterilizing stoves, as well as to the attack of the different antiseptics.

The piston comprises a cylindrical metal body 10 the length of which is, as that of the pump barrel, important relatively to the stroke, for the double purpose of ensuring a perfect guide action and to obtain a fluid-tightness without having recourse to packings or special devices.

A rod 11 secured to the piston 10 or in one piece with the same, is arranged in the axis of the said piston and provided with a crank arm 12 having an operating handle 13 and a boss 14. On the latter is secured, at right angles to the axis of the pump, a finger 15 which serves as a spindle for a roller 16 guided between the flanges of a cam-slot 17 formed in a sleeve 18 internally screw-threaded for screwing on the threaded portion 4 of the armature. The shape and orientation of the cam-slot 17 are determined according to the stroke adopted and according to the law of movement of the reciprocating displacements of the piston.

This law can obviously be of any kind for a medical pump usually actuated by hand and of small dimensions. Thus, for greater simplicity, the flanges of the cam-slot 17 are plane and inclined relatively to the axis of the pump according to the stroke to be imparted to the piston 10. The sleeve 18 is secured on the pump barrel so as to provide a space, as reduced as possible between the bottom 2 and the piston when it is at the end of its stroke. Relating to the angular orientation or setting of the sleeve 18 relatively to the pump barrel, it can be determined by reference marks or by abutments for causing the ports 8 and 9 to coincide with grooves 19 and 20 provided on the side surface of the piston 10, according to the required cycle of operation.

The grooves 19 and 20 of the piston 10 are homologous curves of the cam-slot 17.

They open in the bottom of the piston and correspond, one to the inlet port, the other to the delivery port.

The operation of the pump thus described may be reviewed as follows. If, for instance, it is desired to make an injection, the suction nozzle 7 is connected through a pipe, to the needle (not shown), whilst the delivery nozzle 6 receives a pipe (not shown) for discharging the pumped liquid. The pump barrel being held in one hand, the piston is caused to continuously rotate with the other hand by means of the crank; it receives at the same time reciprocating translations. During the down stroke (Fig. 4) the groove 19 moves opposite the suction port 8 and the pump barrel fills up with the sucked liquid. At the end of the down stroke, the groove 19 ceases to be in contact with the port 8, and during the up stroke the groove 20 moves opposite the port 9 through which is delivered the liquid previously sucked.

After use, the pump can be rapidly taken apart. In fact, it suffices to unscrew the sleeve 18 for separating the piston from the pump barrel and to very easily effect the washing and sterilization of these elements.

What I claim as my invention and desire to secure by Letters Patent is:—

1. In a piston pump for medical purposes of the valveless type, a pump barrel, a rotating and reciprocating piston therein, a hand crank upon the piston for rotating the same, a radial finger upon the said crank, a roller freely mounted upon the said finger, two inclined flanges upon outer surface of the pump barrel and forming guiding members for the roller placed between them.

2. In a piston pump for medical purposes of the valveless type, a pump barrel having an inlet and an outlet in its side walls near its outer end, a rotating and reciprocating piston in the barrel, a hand crank upon the piston for rotating the same, a radial finger upon the said crank, a roller freely mounted upon the said finger, a socket at the inner end of the pump barrel adjacent to the crank, two inclined flanges upon the said socket for receiving between them the roller and to impart to the piston a reciprocating movement in the barrel during the rotation of the crank, and means for readily connecting or separating the said socket and the pump barrel.

In testimony whereof I have signed this specification.

CHARLES MAYER.
